DE WANE B. SMITH
By Milton E. Robinson

ATTORNEY.

UNITED STATES PATENT OFFICE.

DE WANE B. SMITH, OF DEERFIELD, NEW YORK.

DESIGN FOR A BODY FOR BICYCLE-PUMPS.

SPECIFICATION forming part of Design No. 29,986, dated January 10, 1899.

Application filed December 14, 1898. Serial No. 699,272. Term of patent 7 years.

To all whom it may concern:

Be it known that I, DE WANE B. SMITH, a citizen of the United States, residing at Deerfield, in the county of Oneida and State of New York, have invented and produced a new and original Design for a Body for Bicycle-Pumps, of which the following is a specification, reference being had to the accompanying drawings, forming a part hereof.

10 Figure 1 shows a side elevation of my design of bicycle-pump body. Fig. 2 shows a perspective view of the same.

15 The leading or material feature of the design consists in the form and shape of the body as a whole—that is to say, including the

cylindrical portion 1, the stirrup portion 2, and particularly the side projecting portion 3, substantially as shown and arranged.

Having described my invention, what I claim as new, and desire to secure by Letters Patent, is—

The design for a body for bicycle-pumps, substantially as herein shown and described.

In witness whereof I have hereunto set my hand, in the presence of two witnesses, this 10th day of December, 1898.

DE WANE B. SMITH.

Witnesses:

E. WILLARD JONES,
SARAH A. BROWN.
